UNITED STATES PATENT OFFICE.

STEPHEN MARKIS, OF YUKON, PENNSYLVANIA.

MANIFOLDING-MACHINE.

1,174,080.

Specification of Letters Patent.

Patented Mar. 7, 1916.

Application filed July 15, 1915. Serial No. 40,104.

To all whom it may concern:

Be it known that I, STEPHEN MARKIS, a citizen of the United States, residing at Yukon, in the county of Westmoreland and 5 State of Pennsylvania, have invented certain new and useful Improvements in Manifolding-Machines, of which the following is a specification.

This invention relates to manifolding machines and has for its object to provide 10 a machine of such class, in a manner as hereinafter set forth, with means whereby triplicate or original writings can be obtained simultaneously.

15 Further objects of the invention are to provide a machine of such type which is simple in its construction and arrangement, strong, durable, efficient in its use and inexpensive.

20 With the foregoing and other objects in view the invention consists of the novel construction, combination and arrangement of parts as hereinafter more specifically described and illustrated in the accompanying 25 drawings, wherein is shown an embodiment of the invention, but it is to be understood that changes, variations and modifications can be resorted to which come within the scope of the claims hereunto appended.

30 In the drawings wherein like reference characters denote corresponding parts throughout the several views:—Figure 1 is a side elevation of a manifold machine in accordance with this invention. Fig. 2 is 35 a top plan partly in section. Fig. 3 is a longitudinal section. Fig. 4 is a sectional plan. Fig. 5 is an elevation of the scribing member for triplicate writing.

Referring to the drawings in detail 1 40 notes a base having at its rear a bracket 2, to which is hinged as at 3, a casing 4, formed with front, rear, side walls and a top. The base 1 constitutes a bottom for the casing 4 when the latter is swung to engage the 45 upper face of the base 1.

The top of the casing 4 is indicated at 5, and projects forward from the front wall 6 of said casing. The projecting portion of the top 5 and front wall 6 are braced by 50 brackets 7. The top 5 is formed with transversely extending slots 8, 9, 10, 11, 12 and 13. The slots 9, 11 and 13 are of greater width than the slots 8, 10 and 12.

55 The machine includes three web shifting mechanisms which are arranged within the

casing 4 and one of said mechanisms consists of a pair of parallel shafts 14—14^A, arranged near the top of the casing 4, and which is provided with rollers 17—17^A. Secured to the sides of and arranged within 60 the casing 4 is a vertically disposed guide 20, cut away near its top, on one side, as at 23, to form an opening and extending into said opening is a roller 17^C, carried by a shaft 14^C, of a pair of parallel shafts 65 14^C—14^D, journaled in the sides of the casing 4 near the top thereof parallel with the shafts 14—14^A.

Journaled in the sides of the casing 4, 70 near the bottom thereof, is a pair of parallel shafts 24—24', provided with rollers 27 and 27', arranged below the lower end of the guide 20, and are so disposed with respect to the guide whereby the plane of the latter will extend between said rollers 27 and 27'. 75

Journaled in the sides of the casing 4 is a shaft 28, carrying a roll of paper 29. Arranged above the shaft 28 and journaled in the sides of the casing 4 is a shaft 30, upon 80 which the strip or web 31 winds as it winds off the shaft 28, as indicated at 32.

The web 31 passes up through the guide 20, between the rollers 27 and 27', these latter are termed feed-rolls, and associated with the roller 17^C and roller 17^A for winding the 85 web 31 and to cause the web to pass up through the slot 12, over the upper face of the top plate 5, and down through the slot 13 between the rollers 17 and 17^A. The strip or web 31 then winds on the shaft 30. 90

Another of the web shifting mechanisms includes the pair of shafts 14^C—14^D, the rollers 17^C, 17^D, carried thereby, the guide 20, having a slot, a pair of shafts 25 and 25' arranged below the guide and provided with 95 rollers 25^A and 25^B, and shaft 28^A which carries a roll of paper 29^A, shaft 30^A upon which the web or strip of paper winds when it unwinds off the shaft 28^A, and a roller 17^C carried by one shaft of a pair of parallel shafts 14^C—14^D and which extends into 100 the opening formed in the guide 21. The slots 10, 11, associate with the mechanism just described.

The other web shifting mechanism includes the rollers 17^E and 17^F carried by the shafts 14^E and 14^F, a guide 22 having an opening near its top, a shaft 18 carrying a roller 19 which extends into the opening of the guide, a pair of shafts 28 and 28^B ar- 110

ranged below the guide and provided with rollers 26^A and 26^B, a shaft 28^B carrying a roll of paper 29^B, and a shaft 30^B upon which the strip or web winds when it winds 5 off the shaft 28^B. The slots 8, 9, associate with the mechanism last mentioned.

The operation of one of the web shifting mechanisms is as follows:—The winding off of the web 31 from the shaft 28 is caused by 10 the rotation of the rollers 27—27', as the web passes between said rollers, and is also assisted by the rotation of the rollers 17—17', of the shafts 14—14^A. The roller 17^C of the shaft 14^C extends into the guide 20 and assists in the upward feed of the web. The movement of the web 31 downward, to wind upon the shaft 30, is caused by the action of 15 the rollers 17—17' of the shafts 14—14^A, as the web passes down between such rollers, 20 as clearly illustrated in Fig. 3.

Journalized in the sides of the casing 4 is a shaft 33, which projects from one side of the casing 4 and is provided with a crank or handle 36. A shaft 33 has a sprocket wheel 25 37 over which travel sprocket chains 38, 39, and 40 and the said chains lead to a shaft of the pairs of shafts 24—24', 25—25', 26—26'. One of the shafts of the pairs of 30 shafts 14—14^A, 14^C—14^D, 14^E and 14^F and the shaft 18 are operatively connected together by chain connections 40. One of the shafts of the pair of shafts 14^C—14^D is operatively connected to the pulley 37 by a belt connection 41. The shafts 30 are operatively 35 connected with one of the shafts of the pairs of shafts 24—24', 25—25', 26—26' by belt connections 42.

By the foregoing arrangement of the parts it is obvious that as the shaft 33, which 40 is termed the operating shaft, is actuated, the webs of paper will be fed over the upper face of the top 5 of the casing 4.

Fig. 5 illustrates a scribing element which 45 consists of a handle 43 in the form of a pen holder, and which has its lower end provided with a pen point 44. Carried by the handle 43 is a bar 45 having loops 46 at each end, and to which is secured a support 47, provided with a pen point 48. When using 50 the scribing element the bar 45 is positioned longitudinally with respect to the casing 4 and is of such length that when the scribing element is employed that triplicate or original writings will be had upon independent 55 webs. When the scribing element is employed in a manner as stated the pen points 44 and 48 are arranged in a manner so that satisfactory writings may be obtained. The scribing element can also be employed for 60 making triplicate or original writings upon one web and in this connection the pen

points will be adjusted to the desired position.

When adjusting the pen points the supports 47 and handle 43 are shifted within 65 the loops 46 and 49. The bar 45 is formed of two members which are connected together by adjusting screws 50.

What I claim is:—

1. A manifolding device comprising a 70 support for a series of independent webs said support having its top provided with a series of pairs of slots for passage of said series of independent webs, a series of web shifting mechanisms arranged below said 75 top and capable of shifting independent webs up through one of each pair of said slots, then over the upper face of said support, thence down through the other of each pair of said slots, each of said mechanisms 80 including a vertically disposed hollow guide through which the web passes, and said guide being provided near its top with a slot, a feed roll extending into the slot of the guide and engaging the web for shifting 85 the same upwardly, a pair of feed rolls arranged below the guide for withdrawing the web from a source of supply, a winding roll for each withdrawn web, an additional pair 90 of rolls arranged below the top for directing the web to the winding roll, and operating means for moving said webs.

2. A manifolding device comprising a support for a series of independent webs, said support having its top provided with a 95 series of pairs of slots for passage of said series of independent webs, a series of web shifting mechanisms arranged below said top and capable of shifting independent webs up through one of each pair of said 100 slots, then over the upper face of said support, thence down through the other of each pair of said slots, each of said mechanisms including a vertically disposed hollow guide through which the web passes, and said 105 guide being provided near its top with a slot, a feed roll extending into the slot of the guide and engaging the web for shifting the same upwardly, a pair of feed rolls arranged below the guide for withdrawing the web 110 from a source of supply, a winding roll for each withdrawn web, an additional pair of rolls arranged below the top for directing the web to the winding roll, and operating means for simultaneously moving said webs. 115

In testimony whereof I affix my signature in presence of two witnesses.

STEPHEN MARKIS.
